US0D1082541S

(12) **United States Design Patent** (10) **Patent No.:** **US D1,082,541 S**
(45) **Date of Patent:** **** Jul. 8, 2025**

(54) **CONTAINER**

(71) Applicant: **S. C. Johnson & Son, Inc.**, Racine, WI (US)

(72) Inventors: **Brian T. Davis**, Burlington, WI (US); **Julianna Miller**, Boston, MA (US); **Miguel M. Bual**, Lisbon (PT)

(73) Assignee: **S. C. JOHNSON & SON, INC.**, Racine, WI (US)

(**) Term: **15 Years**

(21) Appl. No.: **29/951,682**

(22) Filed: **Jul. 10, 2024**

Related U.S. Application Data

(63) Continuation of application No. 29/706,733, filed on Sep. 23, 2019, now Pat. No. Des. 1,042,134.

(51) **LOC (15) Cl.** **09-07**

(52) **U.S. Cl.**

USPC **D9/503**; D9/504; D9/558

(58) **Field of Classification Search**

USPC D9/500, 503, 504, 549, 550, 553, 556, D9/558, 559, 574, 575, 685, 690, 691, D9/692; D7/507, 509, 510, 513, 523; D28/76, 91

CPC B65D 1/0223; B65D 1/02; B65D 1/10; B65D 83/75; B65D 83/16; A47J 41/0072; A47G 19/2205

See application file for complete search history.

(57) **CLAIM**

The ornamental design for a container, as shown and described.

DESCRIPTION

FIG. 1 is an isometric view of a top, front, and left side of an ornamental design for a container;

FIG. 2 is a front elevational view of the container of FIG. 1;

FIG. 3 is a rear elevational view of the container of FIG. 1;

FIG. 4 is a left side elevational view of the container of FIG. 1;

FIG. 5 is a right side elevational view of the container of FIG. 1; and,

FIG. 6 is a top plan view of the container of FIG. 1.

1 Claim, 4 Drawing Sheets
